UNITED STATES PATENT OFFICE.

CHARLES LEIB, OF PHILADELPHIA, PENNSYLVANIA.

DESIGN FOR A HOOK FOR GARMENTS.

SPECIFICATION forming part of Design No. 33,853, dated January 8, 1901.

Application filed November 10, 1900. Serial No. 36,006. Term of patent 14 years.

To all whom it may concern:

Be it known that I, CHARLES LEIB, a citizen of the United States, residing at Philadelphia, county of Philadelphia, and State of Pennsylvania, have invented and produced a new and original Design for a Hook for Garments, of which the following is a specification, reference being had to the accompanying drawings, forming part thereof.

10 In the drawings, Figure 1 is a top plan view. Fig. 2 is a side view, and Fig. 3 is a top plan view of the shank with the hook portion omitted.

The leading or material features of my design consist in a hook formed of a single strand of wire, the ends being curved to form circularly-curved portions 1 at the inner end, the shank portion 2 comprising the two strands arranged on parallel relation and 20 in close assemblage, the strands being bent upon themselves to form a hook portion 4, the strands of the shank or body portion being curved outwardly at or near the bend of the hook portion 4 to form substantially enlargement 3, the radius of the inner curve of the 25 enlargement 3 being substantially equal to the diameter of the wire strand, whereby the spring formed by the enlargement is of a diameter substantially equal to the width of the hook portion and in the same vertical plane. 30

Having described my invention, what I claim as new, and desire to secure by Letters Patent, is—

The design for a hook for garments, as herein shown and described.

In testimony whereof I have signed my name to this specification in the presence of two subscribing witnesses.

CHARLES LEIB.
